DISC MEMORY UNIT

Charles F. Grossman, Sunnyvale, Calif., assignor to
Ampex Corporation, Redwood City, Calif.

Filed May 11, 1970, Ser. No. 22,905

Term of patent 14 years

Int. Cl. D14—02

U.S. Cl. D26—5

The figure is a front, top and right side perspective view of a disc memory unit showing my new design, the left side being a mirror image of the right side, and the back and bottom being conventionally plain.

I claim:

The ornamental design for a disc memory unit, substantially as shown and described.
